FIG. 1

FIG. 2

FIG. 3

FIG. 4

FIGURE 1 is a front perspective view of a cabinet for trash receptacles showing my design, portions thereof being broken away to indicate indeterminate length.

FIGURE 2 is a fragmentary bottom perspective view of the cabinet of FIGURE 1.

FIGURE 3 is a front perspective view of the cabinet in open position with portions of the article broken away to indicate indeterminate length.

FIGURE 4 is a rear elevational view of the cabinet of FIGURE 3 on a reduced scale.

The side not shown in FIGURE 1 is a mirror image of the side shown while the top is conventionally flat

and unornamented, except for the connecting angles at the ends.

I claim:

The ornamental design for a cabinet for trash receptacles, substantially as shown and described.
